(57) **CLAIM**

The ornamental design for a knife sharpener, as shown and described.

DESCRIPTION

FIG. 1 is a top perspective view of a knife sharpener in accordance with the present invention wherein a sharpening rod is housed in a handle of the knife sharpener;

FIG. 2 is an end view of the sharpening rod of the knife sharpener shown in FIG. 1;

FIG. 3 is a top perspective exploded view of the knife sharpener shown in FIG. 1; and,

FIG. 4 is top perspective view of the knife sharpener shown in FIG. 1 in an assembled configuration with the sharpening rod threaded onto the handle of the knife sharpener.

1 Claim, 3 Drawing Sheets

FIG. 4
